UNITED STATES PATENT OFFICE

117,482

DESIGN FOR A BIRD HOUSE OR THE LIKE

Mildred Mustarkes, Newport, R. I.

Application August 9, 1939, Serial No. 86,569

Term of patent 7 years

To all whom it may concern:

Be it known that I, Mildred Mustarkes, a citizen of the United States, residing at Newport, in the county of Newport and State of Rhode Island, have invented a new, original, and ornamental Design for a Bird House or the like, of which the following is a specification, reference being had to the accompanying drawing, forming part thereof.

The figure is a perspective view of a bird house or the like showing my new design.

The opposite side from that shown is substantially plain.

I claim:

The ornamental design for a bird house or the like, as shown and described.

MILDRED MUSTARKES.
